UNITED STATES PATENT OFFICE

147,336

DESIGN FOR A VENTILATING FAN

John Brandt Koch, Detroit, Mich., assignor to
American Blower Corporation, Detroit, Mich.,
a corporation of Delaware

Application February 20, 1946, Serial No. 126,752

Term of patent 14 years

(Cl. D26—7)

To all whom it may concern:

Be it known that I, John Brandt Koch, a citizen of the United States of America and a resident of Detroit, in the county of Wayne and State of Michigan, have invented a new, original, and ornamental Design for a Ventilating Fan, of which the following is a specification, reference being had to the accompanying drawing, wherein:

Figure 1 is a rear perspective view of a ventilating fan, showing my new design.

Figure 2 is a front elevational view of the ventilating fan.

Figure 3 is a top plan view of the ventilating fan.

Figure 4 is a side elevational view of the ventilating fan.

Figure 5 is a rear elevational view of the ventilating fan.

Figure 6 is a bottom plan view of the ventilating fan.

I claim:

The ornamental design for a ventilating fan, substantially as shown.

JOHN BRANDT KOCH.
